UNITED STATES PATENT OFFICE

CLARENCE FLINT, OF BIRMINGHAM, ENGLAND

IDENTIFICATION DEVICE FOR UMBRELLAS, WALKING STICKS, AND THE LIKE

Application filed August 2, 1929, Serial No. 382,931, and in Great Britain April 13, 1929.

This invention relates to identification devices for attachment to umbrellas, walking sticks and the like for the purpose of enabling the same to be readily identified or, 5 in the event of loss, to be returned to the owner.

The object of the present invention is to provide an improved form of identification device which can be readily applied to an 10 umbrella or the like, which is neat and unobtrusive in appearance, and which permits of an umbrella or the like being quickly distinguished from others.

According to the invention the identification 15 device comprises an elastic or resilient ring or clip adapted to detachably surround and grip the shaft or handle of an umbrella, walking stick or the like, a tag or the like carried by the ring or clip, and an identification tablet attached to or carried upon one face of the tag or the like. The elastic ring may conveniently consist of an ordinary umbrella ring adapted to embrace the ends of the ribs of the umbrella to hold the latter 20 closed, and the tag may be composed of leather or other flexible material and may be attached to the ring or clip device by a loop. The tag may carry upon the one face a card holder consisting of a flanged metal 25 frame into which is inserted a card upon which a name and address or other identification mark may be written or applied. Upon the opposite face of the tag an initial letter or ornament may be applied which may 30 carry prongs adapted to be passed through the material of the tag and clenched to secure the card frame in place.

Figure 1 of the accompanying drawings is a view showing the improved identification 35 device applied to an umbrella.

Figure 2 is a view showing the side of the identification device bearing an initial letter.

Figure 3 is a view of the opposite face, showing the card holder applied thereto.

45 Figure 4 is a vertical section through the device.

Figure 5 represents a transverse section through the device.

Figure 6 is a view similar to Figure 3 but 50 with the address card and cover slide re-

moved from the card holder and shown separately.

Figure 7 represents a front elevation and also a plan of the initial letter which is applied to the front face of the tag. 55

Figure 8 shows a modification.

Figure 9 is a vertical section through the same.

Figures 10 and 11 represent further modifications. 60

Referring to Figures 1 to 7 of the drawing, the improved identification device comprises a rubber ring 1, such as an ordinary umbrella ring, adapted to be passed over the handle of an umbrella or walking stick so as to grip the shaft thereof, and, in the case of an umbrella, adapted, when the umbrella is closed, to engage over the ends of the ribs, as shown in Figure 1. Attached to the ring 1 is a leather tag 2 of any desired shape having a strap extension 3 adapted to be passed loosely around the said ring 1 and having its end secured to one face of the tag, to form a loop, whereby the tag can hang freely in a vertical position outside the cover of the 65 closed umbrella, as shown in Figure 1. Attached to the front face of the tag is a metal initial letter device or ornament 4 having integral prongs 5 at its top and bottom edges which are passed through the material of the tag. These prongs serve to secure the end of the loop 3 and also a metal card holder 6, 70 to the opposite face of the tag, as hereinafter described. The card holder 6 comprises a rectangular metal plate or frame having three flanged or turned-over edges adapted to receive beneath them a card 7 upon which the name and address of the owner of the umbrella can be written, and also a celluloid cover 8 which can be slid into the frame over 75 the card. To secure the card holder in position it is laid over the free end of the loop strap 3 and the prongs 5 upon the top edge of the initial letter 4, after being passed through the body of the tag and through the end of the loop strap 3, are clenched down over the top edge of the card-holder 6 into 80 grooves or recesses 9 provided in the back plate thereof, while the prongs on the lower edge of the initial letter are passed through 85

the body of the tag and through the end of the loop strap 3, are clenched down over the top edge of the card-holder 6 into grooves or recesses 9 provided in the back plate thereof, while the prongs on the lower edge of the initial letter are passed through 90

holes in the lower part of the card holder and are clenched over into grooves or recesses 10 in the back plate. The said back plate of the card-holder may be slit longitudinally at 11, 11, to provide a resilient part between the slits adapted to exert pressure upon the card to hold it in place.

The tab, when attached to the umbrella by means of the ring 1, is neat in appearance and provides a ready means for enabling the umbrella to be identified and returned to the owner in the event of being lost. The identification device can be readily observed even when the umbrella is closed, since the tab hangs over the outside of the rolled-up cover, and as the initial letter is presented outwardly an umbrella can be readily distinguished by its owner from a number of other umbrellas of similar appearance. In the form shown in Figures 8 and 9, the address card 6 is adapted to be inserted into a pocket 12 attached to one face of the tag 2, the pocket having an aperture 13 covered by a piece of celluloid 14 through which the card may be seen. The end of the loop strap 3 connected to the ring 1 may be stitched to the face of the tag. The opposite face of the tag to that which carries the card may be plain or may have an initial letter or ornament attached to it.

The modified form of the identification device shown in Figure 10 has a plain metal plate 15 riveted or otherwise secured to the one face of the tag 2, and upon which the name and address of the owner of the umbrella may be engraved. The tag, as in the previous forms, is attached by a loop 3 to the rubber ring 1. The opposite side of the tag to that which bears the plate 15 may be plain or may carry an initial letter or ornament.

Figure 11 represents another modification in which the tag 2 is attached by a loop 3 to a metal spring clip 16 adapted to be sprung on to the shaft of the umbrella.

Having fully described my invention, what I desire to claim and secure by Letters Patent is:

1. An expandible attachment member adapted to be detachably engaged with the stem of an umbrella, walking stick or the like, a tag, a loop at the upper end of the tag engaging loosely with the attachment member, and an identification card holder comprising a flanged plate attached to the one face of the tag.

2. An expandible attachment member adapted to be detachably engaged with the stem of an umbrella, walking stick or the like, a tag, a loop at the upper end of the tag engaging loosely with the attachment member and an initial letter attached to the one face of the tag.

3. An india-rubber ring adapted to be detachably engaged with the stem of an um-

rella, walking stick or the like, a flexible tag, a loop at the upper end of the tag engaging loosely with the ring, an identification card holder comprising a flanged plate attached to the one face of the tag and an initial letter attached to the other face of the tag.

CLARENCE FLINT.
